Atty.

UNITED STATES PATENT OFFICE.

RALPH L. BUCK, OF JAMESTOWN, NEW YORK.

OIL-WELL-CLEANING DEVICE.

Application filed November 22, 1928. Serial No. 149,867.

This invention relates to an apparatus or device for use in the treatment of oil and gas wells, and is primarily designed for reviving old wells so as to increase the flow of oil and gas therefrom.

In the drilling of oil and gas wells, and after the oil sand has been reached, it is customary to explode a shot or charge of explosives to create in the oil sand what is 10 customarily termed a shot pocket, which step augments the flow of oil and gas. As time goes on the flow of oil or gas from the well will decrease by reason of the gradual formation of a coating or lining of paraffin, and 15 the other thickened products of petroleum, on the walls of the shot pocket which retards the flow of oil from the oil sand into such shot pocket. Consequently after this coating of paraffin or other deleterious material in the oil or shot pocket of the well is 20 removed, the oil will again have a free outlet into the pocket and the volume of flow will consequently be increased, if not restored to its normal capacity.

Various attempts have been made to restore or increase the flow of oil or gas, such as by the introduction of heated billets of metal into the well casings and dropping water thereon so as to generate a quantity 25 of steam for acting upon the coated walls of the shot pocket. Such method, however, has proved impractical, principally because the billets quickly cool and lose their steam-producing temperature, thereby necessitating the withdrawal of the billets from the well casing for being reheated. Furthermore in the use of heated billets the temperature of the latter gradually decreases from 30 its greatest heat to a temperature below a practical steam-producing degree with the effect that the efficiency of such method can be calculated on the average or mean temperature.

Other schemes have been devised to provide an efficient steam generating apparatus, involving the use of a combustible material disposed in a casing and adapted to be lowered into the oil bearing portion of the well for maintaining the temperature of a steam-producing surface at its maximum efficiency. 45 Such devices however, are open to the objection that by reason of their operative lo-

cation it has been impracticable to supply to the combustible material the necessary oxygen required to support combustion.

The aim of the present invention is to provide a highly efficient oil and gas well treating device for generating steam and directing it outwardly into the oil or shot pocket, wherein the use of billets is eliminated, and wherein the generation of steam is continuous and without interruption so that the dissolving or removal of the paraffin or other coating may be fully and completely effected in a single operation; and it has for 55 its objects to provide an electrically heated steam generating apparatus for the production of steam to be discharged into the shot pocket of the oil or gas well; to provide an improved construction by which steam may quickly be generated, more in the nature and operation of a flash boiler; to provide a steam generating apparatus in which the steam is practically superheated by being caused to travel a definite and well heated path before it is 60 discharged into the shot pocket of the oil or gas well; to provide an improved and safety feed for controlling the flow of water onto the heated surface of the steam generating apparatus.

The invention further resides in the salient features of construction and the novel arrangements and combinations of parts hereinafter set forth, reference being made to the accompanying drawings wherein;

Fig. 1 is a side elevation of an oil or gas well treating device constructed in accordance with the present invention, portions thereof being shown in section.

Fig. 2 is an enlarged longitudinal section 70 through the upper portion of the steam generating apparatus or flash boiler.

Referring more in detail to the accompanying drawings, and with particular reference to the electric flash boiler or steam generating apparatus, the numeral 1 designates a casing or housing preferably of cylindrical form and having its lower end closed by a plug or closure 2, threaded thereto, and its upper end closed by a ring or annular plug 3 threaded into the upper end of the casing, said annular plug having an encircling flange for seating on the upper edge of said casing, as indicated at 4.

Adjacent its upper end the casing is provided with a plurality of steam discharging openings 5 of any desired number which are shown as inclining downwardly and outwardly whereby the steam will be discharged in downwardly directed jets against the coated walls of the shot pocket. Above the steam discharge openings 5, the internal diameter of the casing is enlarged, thereby forming an internal shoulder 6 on which seats a peripheral flange 7 of a cylindrical outer shell 8. Within the outer shell and preferably concentric therewith is an inner shell 9, which extends upwardly through the annular closure plug 3, where it is threaded for the application of a cap 10, the latter preferably engaging on said closure plug 3. The inner and outer shells extend down coextensively into the housing to a point in proximity to the lower plug 2, where the said lower ends of said shells are connected as indicated at 11, either by welding, or the two shells might be stamped from a single sheet of metal or formed integral throughout by any suitable machine method. The flange 7 is preferably formed by turning out the top edge of the outer shell, it being observed that said flange suspends the shell structure from the shoulder 6 except as to what support is accorded the inner shell by the plug 3 and the cap 10. Such a flash surface or shell construction provides an annular heating chamber 12 in which is disposed the electric heater consisting of a tubular support 13, preferably of porcelain or other suitable insulating body, and an electric resistance unit 14, the resistance unit in the present instance being shown as a coiled wire wound helically about the tubular support 13, the latter having its periphery spirally grooved, as indicated at 15, so that the resistance element may be inset from the periphery of the tubular support. This tubular support is substantially coextensive with the chamber of the shell construction, and it has its upper end provided with a peripheral flange 16 to overhang and seat on the flange 7 of the outer shell, a packing 16' of asbestos or other suitable material being preferably interposed between the two flanges 7 and 16. By reason of the resistance unit 14 being disposed in the outwardly opening groove 15, the greatest heat will be directed against the outer shell 8, and as the steam ascends in the annular steam space 17, as defined by the outer shell 8 and the encircling casing 1, it will be superheated to such a degree by the time it emerges from the openings 5 that its action and effect on the coating or lining of the shot pocket will be immediate and almost instantaneous.

A channeled washer 18 surmounts the upper end of the tubular support 13 and is packed relatively thereto by means of the

two annuli of asbestos 19 and 20. The bottom of the upper closure plug 3 is preferably shaped to fit the channeled washer 18 so that when the closure plug 3 is screwed home it will wedge the annuli 19 and 20 against the housing 1 and the inner shell 9, respectively, and against the upper end of the tubular support 13 to seal the heating unit, and through these annuli exert a clamping pressure on the flanges 7 and 16, against the shoulder 6, so as to secure them and their connected elements in position.

A water container or supply of any desired or suitable capacity is provided for furnishing water to the electric flash boiler just described, the container being generally shown as comprising a casing 21 closed at its lower end by a threaded plug 22 and at its upper end by a threaded plug 23. Water may be supplied to the container 21, if desired, by means of a supply pipe (not shown) threaded into the filling opening 24 provided in the upper plug 23. For small operations the filling opening may be closed by a plug 24' after the container has been filled. A feed pipe 25 extends through the bottom plug 22 and the cap 10 for establishing communication between the water container and the flash boiler, said feed pipe terminating in the upper end of the inner shell and being so formed as to discharge its water onto the inner wall of said inner shell 9, whereby the heated inner shell will immediately begin heating the water and start the conversion of the same into steam. A vent pipe 26 also extends through the bottom plug 22 and the cap 10, terminating at its upper end in the upper portion of the water container and at its lower end at a predetermined point in the lower portion of the flash boiler. If, for any reason, there should be a flow of water from the container to the flash boiler while the electric heater is not in operation, the water will gravitate to the bottom of the flash boiler and the flow will continue until the level of the water in the bottom of the flash boiler enters the lower end of the vent pipe 26 and rises to the level of the water in the container 21, thereby automatically stopping the flow of water. Obviously, should there be any water in the lower part of the flash boiler when the electric heater is turned on, the pressure of the steam generated within the inner shell will gradually force the water from the inner shell outwardly into the steam space 17 where it will be converted into steam without in any way obstructing the escape of steam from the discharge openings 5. The pipes 25 and 26 are preferably welded or tightly joined to the cap 10 where they penetrate the same, and to relieve the pipes of supporting strain in suspending the flash boiler from the water container, a plurality of rods 27 are threaded at their respective ends

ends into the annular closure plug 3 and the plug 22. The upper closure 23 of the water container may be provided with an eye or loop 28 for supporting and adjusting the general assembly within a well casing.

In the operation of the oil or gas well treating device as just described, the same is lowered into the shot pocket of the well, and the electric heater turned on. The ground or circuit wires (not shown) are extended from the electric heater upwardly to the top of the well and connected to any convenient switch whereby the control of the heating device may be readily accomplished from an accessible point. With the flow of water from the container to the flash boiler being predetermined, and the water replenishment to the container being governable by means of a valve (not shown) 20 piped to the filling opening 24, the water will trickle or flow down the interior of the inner shell which is sufficiently heated to generate steam, whereupon the generated steam will find its escape about the lower 25 end 11 of the shell construction and up through the steam space 17, where it will be highly heated or superheated, and out through openings 5. Obviously, the conversion of the water into steam will create a 30 pressure within the inner shell 9 so that the steam will be forced around the lower end of the shell construction, and being further heated as it ascends in the space 17, will escape through the openings 5 under sufficient 35 pressure to direct the jets downwardly and against the coated wall or lining of the pocket. The film of water may be spread over the inner surface of the inner shell by the provision of suitable grooves or baffles (not shown). The watery film, as it flows 40 down the inner shell will quickly be converted into steam, and any water which should pass to the outer shell will be forced up over said highly heated outer shell where its conversion will be almost instantaneous. The 45 supply of steam will be continuous and steady and, by reason of the location of the openings 5 adjacent the upper end of the flash boiler and also because of the fact 50 that the rising steam in the space 17 is highly heated or superheated, the temperature of the steam emitted from the openings 5 will be at a most efficient degree for quick melting or dissolving the lining of the shot 55 pocket. Consequently the removal of the lining or coating will consume but a short interval of time and after one portion of the lining or coating has been removed the well treating device or apparatus may be lowered 60 or elevated so that the jets of steam will act upon an adjacent portion of the coating or lining.

With the use of the improved device the coating or lining of the shot pocket may be entirely removed or dissolved without

withdrawing the device from the well, and consequently the dissolving of such coating or lining is considerably expedited and facilitated. The construction and assembly of the flash boiler is quite novel and simple; 70 the several parts being readily removable and insertible into the casing so that in the event of any injury to any of the parts, or their failure to properly function, the device may quickly be taken down and repair made, 75 without the loss of valuable time and without much expense. The form, shape and arrangements of the several parts have obviously been set forth in detail for the sake of clearness in the foregoing description without any intention of limiting the scope of my invention beyond that prescribed by the appended claims.

I claim:

1. An oil and gas well cleaning device 85 comprising inner and outer concentric shells joined at their lower ends and defining a heating chamber between the shells, a heating means arranged in the heating chamber between said shells, means for feeding water 90 onto the inner surface of the inner shell adjacent its upper end whereby the water will flow down the heated inner shell and be converted into steam, the steam and unconverted water passing about the lower 95 ends of the shells to the outer shell for further heating, and means for discharging the steam from the surface of the outer shell in an outward direction.

2. An oil and gas well cleaning device 100 comprising a tubular casing having steam discharge openings through its periphery adjacent one end, the opposite end of said casing being closed, an annular plug threaded into said first end of the casing, an inner shell extending through the annular plug into the casing, the outer end of said shell being closed, a water feed pipe piercing the closed outer end of the shell for discharging water onto said shell, and means for heating 105 said shell within the casing whereby the water is converted into steam for discharging through the openings of the casing.

3. An oil and gas well cleaning device 110 comprising a tubular casing, closed at one end and open at its opposite end, said casing being provided with steam discharge openings adjacent its open end, the said open end of the casing having its diameter enlarged 115 to form an internal shoulder between the openings and said open end of the casing, a shell supported by the shoulder and defining with the casing a space with which the casing openings communicate, means within the shell for heating the same for converting water fed to the shell into steam, and means for supplying water to the shell.

4. An oil and gas well cleaning device 120 comprising a cylindrical casing closed at one end and open at its opposite end, the 125

comprising a casing having steam discharge openings, a steam generating surface within the casing and extending toward the openings thereof, and means for heating the surface to a higher temperature adjacent the casing openings than at a point more remote.

5 12. An oil and gas well cleaning device

comprising a casing having steam discharge openings, a steam generating surface within the casing and extending toward the openings thereof, and means for heating the surface with an increasing temperature as the surface approaches the casing openings.

10 RALPH L. BUCK.

CERTIFICATE OF CORRECTION.

Patent No. 1,672,200.

Granted June 5, 1928, to

RALPH L. BUCK.

It is hereby certified that error appears in the printed specification of the above numbered patent requiring correction as follows: Page 1, line 68, strike out the words "charged into" and insert instead the syllable and words "tion of steam in"; page 2, line 45, after the word "chamber" insert the numeral "12"; and that the said Letters Patent should be read with these corrections therein that the same may conform to the record of the case in the Patent Office.

Signed and sealed this 31st day of July, A. D. 1928.
